UNITED STATES PATENT OFFICE.

REGINALD P. BORGA, OF SOUTH NORFOLK, VIRGINIA, ASSIGNOR OF TWO-THIRDS TO SAMUEL W. LYONS, JR., OF NORFOLK, VIRGINIA; DORA A. BORGA ADMINISTRATRIX OF SAID REGINALD P. BORGA, DECEASED.

CAR-STAKE.

1,081,807.

Specification of Letters Patent.

Patented Dec. 16, 1913.

Application filed January 28, 1913. Serial No. 744,683.

To all whom it may concern:

Be it known that I, REGINALD P. BORGA, a subject of the King of Norway, but having declared my intention of becoming a citizen 5 of the United States, residing at South Norfolk, in the county of Norfolk and State of Virginia, have invented a certain new and useful Improvement in Car-Stakes, of which the following is a full, clear, and exact description.

The primary object of this invention is to provide an unloading means by which logs and other long bodies piled upon one another on a flat car, may be discharged laterally without damage to attendants or harm 15 to the load-confining means.

The invention consists of portable or separable stakes, applied to the sides of the car for confining the load during transit, each 20 stake composed of a member stationary on the car and another member detachably connected with the stationary member, and capable of release therefrom so as to swing out with and away from the escaping load, and 25 adapted to be replaced for another load.

The invention is capable of use in connection with ordinary stake-pockets, and it may also be used without such stake-pockets; and it is susceptible also of other variations.

30 In the accompanying drawings illustrating the invention, in the several figures of which like parts are similarly designated, Figure 1 is a side view of part of an ordinary flat car supplied with one form of the invention. Fig. 2 is an end view showing the stake released for discharging the load. Fig. 3 is an elevation and partial section of one of the stakes. Fig. 4 is a similar view taken at right angles to Fig. 3. Fig. 5 is a 35 side elevation of the socket member. Fig. 6 is an elevation of the upper end of the latch member of the stake, showing upwardly extending side walls to aid in alining the socket member. Fig. 7 is a top plan view of 40 the latch member.

The portable or separable stake comprises two main parts, namely, a socket member 1, made hollow to receive a wooden or other stake 2 of any sort, and a latch member 3 45 adapted to fit in an ordinary stake-pocket 4, or to be fastened to the side of the car directly. The socket member has a hinge knuckle 5 projecting outwardly from its front and provided with an eye 6; a flat portion 7 provided with a hole 8, and a pecul-

iarly formed undercut notch 9 at its rear. The latch member is made up of a casing 10, provided at its top with the pair of outwardly projecting hinge knuckles 11 between which the socket knuckle 5 fits, and the knuckles 11 likewise have eyes 12 to aline with the eye in the knuckle 5 to receive a connecting pin 13 so as to connect the socket and latch members. The parts 5 and 11 constitute when united a knuckle-joint. 65 One of the eyes 12 may have the notch 14 to receive a key or spline or feather 15 on the pin 13, and inside the knuckle is a groove 14* into which the key 15 is turned, the notch 14 and groove 14* being continuations of one 70 another and forming substantially a bayonet-joint slot. By this means the pin 13 is prevented from accidentally turning and working out. The upper end of the casing 10 is made with an overhanging, hook-like 75 lug 16, of a shape to fit the undercut notch 9 in the socket member so as to retain the socket member against vertical and lateral or forward displacement until released. The lower end of the casing is made hollow, with 80 one side 17 longer than the other to provide a fulcrum, and having an eye 17* to receive a bar for releasing the latch, presently described, when the parts are operated by hand. Within the casing 10 is a vertically 85 disposed spring latch-bolt 18 adapted to engage the hole 8 in the socket member coöperating with the hook-like lug 16 to hold that member in place when the connecting pin 13 is withdrawn. 90

19 is a plate to hold the spring bolt in the casing. This bolt has a laterally extended eye-piece 20 extending substantially to the bottom level of the fulcrum side 17, so that a bar 21 (see dotted lines Fig. 3) may 95 be inserted therein and the fulcrum used as such for said bar to retract the bolt.

If desired, a cross-pin 22 may be used to secure the latch-member in the stake-pocket 4. 100

The stakes on opposite sides of the car are secured by any suitable tying medium 23, such as a chain, rope, wire, bar, or other device, as shown in Fig. 2. When the car is to be unloaded, the pins 13 are withdrawn in 105 any suitable way, and then the latch-bolts are released so that the pressure of the load will force the socket-members out of engagement, and these will fly out as indicated in Fig. 2, with the load but free of it. 110

Any suitable means may be used for releasing the latch bolts, in sets or otherwise, without liability of the attendant getting in the way of the falling load. One such means consists of a rock-shaft 24 supported beneath the side sill and having as many arms 25 as there are bolts and connected with the bolt eye-pieces 20 by links 26, so that by rocking the shaft, as by a lever 27, the several bolts, of a set or otherwise, may be released simultaneously.

It will be observed that the bolts and interlocking lugs and notches hold the stakes while the pins 13 are withdrawn, and that the stakes do not separate until the bolts are released, and hence the unloading may be effected with safety to the attendant. It will also be noted that no chopping away of stakes is necessary in unloading, and these stakes instead of being buried under the load, swing clear of it, and so are ready for re-use.

As shown in Fig. 6, the sides 28 of the casing may be extended upwardly to about the height of the lug 16, to aid in holding the socket-member in engagement with the latch-member.

Where the stakes are used upon cars already in service, the bolts may be released by the bars, as already described, or they may have chains or hooks applied to them for the time being so as to be operated from the opposite side of the car.

What I claim is:—

1. A car stake, having a socket-member adapted to be secured to the bottom end of a wooden or other stake and a latch-member adapted to be secured to the side of a car, said socket-member and latch-member provided with interengaging parts, and means to disconnect the two members so that the socket-member may swing outwardly from above the latch-member with and clear of the load.

2. A car stake, comprising a socket-member, and a latch-member, these members having complementary knuckle-joint parts, connecting means for such knuckle-joint parts, and means to hold the members together when said connecting means is removed.

3. A car stake, comprising a socket-member adapted to receive a stake extension, and provided with a knuckle, a hole in its bottom and a rear notch, and a latch member adapted to be fitted to a car side and provided with complementary knuckle-parts, a spring latch-bolt to engage the hole in the socket-member, and a lug to engage the notch in the socket-member.

4. A car stake, comprising a socket-member having a hollow upper part and a bottom part made with an outwardly extending eye portion, a rear notch and a hole

between these two, and a latch-member having eye parts, means to engage the several eye parts, a lug to engage the notch and an intermediate spring bolt to engage the hole, and means to release the bolt.

5. A separable stake, composed of a latch-member adapted to be fitted to a car and having a spring bolt, a fixed hook-like lug, and knuckle-joint parts, and a socket-member having a hole to receive the bolt, an undercut notch to engage the lug and a complementary knuckle-joint part.

6. A separable stake, composed of a latch-member adapted to be fitted to a car and having a spring bolt extending downwardly and provided with a releasing eye, a fixed hook-like lug, and knuckle-joint parts, and a socket-member having a hole to receive the bolt, an undercut notch to engage the lug, and a complementary knuckle-joint part.

7. A separable stake, composed of a latch-member comprising a casing one of whose lower sides is extended to form a fulcrum, said casing adapted to be fitted to a car and having a spring bolt, a fixed hook-like lug, and knuckle-joint parts, and a socket-member having a hole to receive the bolt, an undercut notch to engage the lug, and a complementary knuckle-joint part.

8. A separable stake, having a socket-member provided with a knuckle-joint part, and a latch-member having complementary knuckle-joint parts, said knuckle-joint parts having eyes, and a pin adapted to be inserted in said eyes and locked therein.

9. A separable stake, having a socket-member provided with a knuckle-joint part, and a latch-member having complementary knuckle-joint parts, said knuckle-joint parts having eyes, one of such parts having a bayonet-joint slot, and a connecting pin inserted in said eyes to connect the parts and having a key engaging the bayonet-joint slot to lock said connecting pin in place.

10. A separable stake, comprising a stationary latch-member having knuckle-joint parts, a spring latch, a hook-like lug, and upwardly extending sides alongside the lug, and a movable and separable socket member having a knuckle-joint part adapted to be connected with the corresponding parts on the stationary member, a hole to be engaged by the latch, and an undercut notch to be engaged by the lug, and fitted between the extended sides of the stationary member.

In testimony whereof I have hereunto set my hand this 27th day of January A. D. 1913.

REGINALD P. BORGA.
